UNITED STATES PATENT OFFICE.

HAROLD W. FLETCHER, OF HOUSTON, TEXAS, ASSIGNOR TO HUGHES TOOL COMPANY,
OF HOUSTON, TEXAS, A CORPORATION OF TEXAS.

PIPE WRENCH.

Application filed June 27, 1922. Serial No. 571,234.

This invention relates to improvements in pipe wrenches and more especially to that type of pipe wrench used for screwing and unscrewing sections of casing, drill stem, or tubing employed in well drilling.

One object of the present invention is to provide a wrench of the heavy oil well type which will have a wide range of adjustability and which can be applied to a pipe and locked thereon with a minimum loss of time and labor.

Another object of my invention is to provide a pipe wrench which will have a firm gripping action upon the pipe to be screwed or unscrewed without also tending to mutilate or crush the pipe.

Referring to the drawing forming a part of this specification and in which like numerals of reference are applied to like parts in each of the views, Fig. 1 is a top plan view of a wrench embodying my invention, showing the pipe in transverse section. Fig. 2 is a similar view showing the jaws in slightly different relative positions. Fig. 3 is a diagrammatic view of the head and jaws illustrating the flexibility of my construction.

In a construction of my improved type of wrench I employ a handle 8 having, at its rearward end, an eye 9 for attachment to a cable when desired. The forward end of the handle is formed into a head 10 having a laterally projecting arm 11 thereon, said arm being provided with an opening 20 to receive a pin 12 forming a pivotal attachment for a segmental jaw 13. Said jaw 13 is pivoted at its other end, by means of a pin 14, to a second segmental jaw 15, the forward end of which is hooked at 16 to provide a transverse groove or recess 17 to receive a latching yoke or link 18. The form of the yoke 18 is somewhat U-shaped, the legs of which are pivoted to the head of the wrench at 19 and said yoke is adapted 30 to swing on the axis of the pin 19 and engage the hooked end of the jaw 15. A handle 20 at the outer end of said latch facilitates its operation. A similar handle 21 on the outer face of the jaw 15 assists the operator in handling said jaw.

The inner faces of each of the jaws are formed each with a transverse groove therein to receive a triangular shaped tooth 22. As shown in the drawings, I contemplate

using but one tooth on each of the jaws 13 and 15. These teeth will be placed in positions diametrically opposite to each other when the wrench is applied to the particular size of the pipe to which it is best adapted. They will be made of a special hardened steel, and when the jaws are drawn together against the pipe the full force of the clamping action of the jaws will be exerted at the two approximately opposite points where the teeth contact with the pipe; thus the teeth will be forced to grip firmly upon the pipe and prevent the rotation of the pipe within the jaws.

In operation, this wrench is very flexible. It will accommodate itself to varying sizes of pipe in a manner which is unusual with this heavy type of tool. The pivot 19 of the latching yoke is approximately in the line of the central axis of the handle as shown in Fig. 3. The pivotal point 12 of the jaw 13 is offset materially to one side of this axis; thus, when the handle is moved to the right as shown in Fig. 3, supposing the jaw 13 to remain stationary, the forward end 16 of the jaw 15 will be drawn inwardly toward the jaw 13 to clamp the teeth against the pipe. The handle 8 may be considered as fulcrumed at the pivotal point 12 on the jaw 13. The handle here forms the lever and the load will be exerted through the latching yoke and jaw 15 secured to the lever at the pivotal point 19. It will then be obvious that the swinging of the handle will exert a greater force upon the jaw 15 when the handle is in the position shown in full lines in Fig. 3, than when said handle has moved around into the position shown by the dotted line A. For, when the handle is in the position as shown in full lines, the force will be exerted upon the load along the line B and when the handle is in the position shown by line A the load will exert a pull along the line C. It will be seen that the angle formed between the lines E and C will be a right angle and that the resultant load exerts a pull at a point farthest from the fulcrum when this angle is a right angle than when the angle is an obtuse angle as is shown when the handle is in the first position shown in Fig. 3. When the handle is swung still farther into the position shown at D, the resultant load, shown by line F, will move closer to the ful-

crum and the power exerted upon the jaw will be greater, the force being considered constant.

By bending the forward end of the head of the handle so as to offset the pivotal point 5 it will be observed that a greater flexibility of the wrench will be obtained. When the handle is in the position shown in full lines in Fig. 3, it will be adapted to receive 10 a large pipe as shown in Fig. 1, but when a smaller pipe is to be gripped by this wrench, the handle will be swung farther around into the A or D position as far as necessary 15 to properly clamp the size of pipe desired. This position of the wrench is shown in Fig. 2. This adjustability of jaws for different sizes of pipe could not be obtained except with this particular formation of the head of the wrench and the particular means by 20 which the jaws and yoke are pivoted. It will also be seen from Fig. 3 that the force exerted upon the pipe will not increase greatly as the jaws are clamped against the pipe, for the tendency will be to decrease the 25 clamping action slightly as the handle is swung relatively to the jaws. It will be decreased until the handle reaches the position as shown by line A and will then increase somewhat due to the fact that the load is, 30 in effect, nearer the fulcrum. There will, however, be no extremely heavy clamping action tending to crush or mutilate the pipe as the handle is swung in the direction necessary to unscrew the joint.

35 The forming of but two teeth makes it possible to exert the full force of the clamping action at the two opposed points; thus, tending to cause the teeth to bite into the pipe and prevent it from slipping. This is an especially efficient type of gripping means. It is now believed that the advantages of this type of construction will be 40 fully understood by those skilled in the art without further description.

45 What I claim as new and desire to protect by Letters Patent is:

1. In a pipe wrench, a handle, a head thereon having two openings therein, the

forward one offset from the central axis of the handle the other opening being located 50 upon said axis, a segmental jaw pivoted in said forward opening, a second jaw pivoted to said first named jaw, a latching member pivoted in the rear opening and engaging said second jaw whereby said jaws are given 55 a wide flexibility of movement toward and from each other as said handle is swung laterally.

2. In a pipe wrench, a handle, a segmental jaw pivoted at one of its ends to the 60 forward end of said handle, and offset laterally from the central axis thereof, a latching yoke pivoted to said handle at a point spaced to the rear and to one side of said 65 jaw, a second jaw pivotally connected to said first-named jaw and having means to engage said latch, a single tooth on each of said jaws arranged approximately opposite each other, means to manipulate said second jaw and means to manipulate the latch, said latch 70 being adapted to be released by movement of said handle in one direction.

3. In a pipe wrench, a handle, a forward head bent laterally and provided with an opening constituting a fulcrum, a jaw pivoted in said opening, a second jaw pivoted to the first jaw, a latching yoke pivoted to 75 said head centrally of said head and to the rear of said fulcrum, said latch engaging with said second jaw to draw it toward said 80 first-named jaw and acting to give the jaws a wide range of adjustability as said handle is moved in one direction.

4. In a pipe wrench, a handle, a head having a laterally curved forward end, a pipe 85 engaging jaw pivotally secured on said curved end, a second jaw pivotally connected to the first said jaw, a hooked end thereon, and a yoke pivoted centrally of said head to the rear of said curved end and adapted 90 to engage over the hooked end of said second jaw.

In testimony whereof, I hereunto affix my signature, this the 24th day of June, A. D. 1922.

HAROLD W. FLETCHER.
